UNITED STATES PATENT OFFICE.

HENRY TUCKER, OF LAKEWOOD, NEW JERSEY.

GUARD AND STOP FOR IRONING MACHINES.

Application filed May 8, 1926. Serial No. 107,736.

This invention relates to a guard and stop for ironing machines, and while I have shown my invention in connection with a particular type of ironing machine I would 5 have it understood that my invention is applicable to other forms of ironing machine with but slight modification.

The primary object of the invention is to provide a guard which will be moved when 10 the hands of the operator pass too far over the roll and in a position where the operator may be burned so as to cause the machine to stop and hence prevent the burning of the hands, which is common with ordinary machines.

With these and other objects in view, the invention consists in certain novel features of construction and combinations and arrangements of parts which will be more fully 20 hereinafter described and pointed out in the claim.

In the accompanying drawings—

Figure 1 is a view in end elevation of an ironing machine equipped with my improvements;

Figure 2 is a view in front elevation;

Figure 3 is an end view opposite the end view shown in Figure 1 with a portion in section;

Figure 4 is a fragmentary view in front elevation, showing the parts in a different position from that illustrated in Figure 2.

1 represents the frame of the ironing machine, and 2 the pivoted frame which supports the roll 3. 4 represents the shoe of the iron, the surface of which is concentric with that of the roll so that when the material is passed between the roll and the shoe it is ironed in the ordinary manner.

40 I have illustrated in dotted lines in Figure 1 a standard type of power transmission to the ironing roll which consists of an electric motor 6 which drives a gear train 7 to drive a shaft 8 and bevel gears 9, one of which is directly connected to the roll 3.

10 represents a fixed contact and 11 a movable contact which is secured to a spring contact arm 12. 13 is a bell crank lever, the lower member of which is adapted to be moved to the right of Figure 1 by the operator's foot to move the other member of said bell crank lever downwardly and force the contacts 10 and 11 together, overcoming the tension of the spring contact arm 12.

55 The bell crank lever 13 is secured to a shaft 14 which carries an arm 15, and this

arm 15 at its free end carries a finger 16 which is adapted to engage a catch 17 so as to hold the contacts 10 and 11 together when the bell crank lever is moved to starting 60 position.

18 represents the source of electricity, one terminal of which is connected by a wire 19 with contact 10. The other terminal is connected by a wire 20 with one terminal 21 of motor 6. The other terminal of the motor 6 is connected by a wire 23 with the spring contact arm 12.

The catch 17 above referred to is gravity operated and is pivotally connected to a supporting bracket 24. This bracket 24 also supports a pivoted armature 25 connected by a link 26 with the catch 17. Above the armature 25 I have indicated an electromagnet 27. One terminal of this magnet 75 27 is connected by a wire 28 with a source of electricity 29, said source of electricity being also connected by a wire 30 with a contact 31 on a fixed plate 32. Another contact 33 on the fixed plate 32 is connected 80 by a wire 34 with the other terminal of the magnet 27.

34 represents my improved guard, which is in the form of a plate extending above the shoe 4 and projecting forwardly over a portion of the roll 3. This plate has an upwardly turned forward free edge 35 and has flanges 36 at its ends, said flanges being pivotally connected to the shoe, as shown at 37. Coil springs 38 connect the flanges 36 90 with the ends of the shoe 4 and serve to hold the guard in normal position.

A rod 39 is pivotally connected to one of the flanges 36, as shown at 40, and projects through the plate 32, and carries a U-shaped 95 contact 41 at its lower end so that when the free end of the guard 34 is moved upwardly this contact 41 will be moved upwardly to engage both of the contacts 31 and 33 and close the circuit between the source of electricity 29 and the electromagnet 27. When this magnet 27 is energized it will draw the armature 25 upwardly elevating the catch 17 and releasing the finger 16. The spring contact arm 12 will then separate the contacts 100 11 and 10 and move the parts to the position shown in Figure 4, instantly stopping the machine.

The operation is as follows:

Assuming the parts to be in the position 110 shown in Figure 1, the operator passes the article to be ironed over the roll 3 when

the latter is moved to proper position relative to the shoe 4, the starting being accomplished by the movement of the bell crank lever 13 to close the circuit through the contacts 10 and 11 to the motor 6. If the operator's hands should move too far over the roll 3 they would come in contact with the guard 34 and elevate the latter. The upward movement of this guard 34 will 10 through the medium of the parts above described energize the magnet 27 to elevate the catch 17 and immediately stop the operation of the machine, thus preventing any possibility of the operator accidentally burning her hands by contact of the shoe.

Various slight changes and alterations might be made in the general form of the parts described without departing from the invention and hence I do not limit myself 20 to the precise details set forth but consider myself at liberty to make such slight changes and alterations as fairly fall within the spirit and scope of the appended claim.

I claim:
25 In combination with an ironing machine

having a roll and a shoe, an electric motor transmitting motion to the roll, a spring contact arm having a contact thereon, a fixed contact, said contacts included in an electric circuit with the motor and a source of electricity supply, a bell crank lever adapted when moved in one direction to bend the spring contact arm so as to swing the contacts together and close the circuit to the motor, an arm fixed to move with the bell crank lever, a pivoted catch engaging said arm and holding the parts in operative position, a guard supported on the shoe and projecting above the roll, an electromagnet adapted when energized to cause the catch 40 to be moved to release the arm and permit the first-mentioned contacts to be separated by the movement of the spring contact arm, and circuit closing means included in circuit with the magnet and a source of electricity, said circuit closing means being operated by the upward movement of the guard.

HENRY TUCKER.
